UNITED STATES PATENT OFFICE.

LOUIS D'ELIA, OF NEW YORK, N. Y.

SKIRT-MARKER.

No. 923,029.

Specification of Letters Patent.

Patented May 25, 1909.

Application filed August 21, 1908. Serial No. 449,585.

To all whom it may concern:

Be it known that I, LOUIS D'ELIA, a citizen of the United States, and a resident of the city of New York, borough of Manhattan, in the county and State of New York, have invented a new and Improved Skirt-Marker, of which the following is a full, clear, and exact description.

This invention relates to certain improvements in skirt markers, and more particularly to adjustable clamping means for holding the skirt after gripping the lower portion of said skirt, and to constitute a guide for a marker.

The object of the invention is to provide means for gripping the skirt substantially throughout the entire circumference of the lower portion thereof and adjustable so as to grip it at any desired height, and adjustable to receive skirts of any desired size.

Reference is to be had to the accompanying drawings, forming a part of this specification, in which similar characters of reference indicate corresponding parts in both the figures, and in which—

Figure 1 is a top plan view of a device constructed in accordance with my invention; and Fig. 2 is a vertical section on the line 2—2 of Fig. 1.

In the specific construction illustrated in the accompanying drawings, I provide a stationary platform or base, having outer and inner portions 10 and 11, separated by an annular channel or groove 12. The inner platform portion 11 has an outer circumference substantially equal to the circumference of the smallest skirt for which the device may be employed for marking, while the outer circumference of the channel or groove 12 is substantially equal to the circumference of the largest skirt which the device may be employed for marking.

Within the inner platform portion 11 is a second platform 13, upon which stands the person whose skirt is to be hung. This second platform is vertically adjustable, so that it may be raised above or below the level of the main platform or base. Any suitable means may be employed for varying the elevation, but, as shown, the inner platform 13 is provided with a rack bar 14 on one side thereof and in engagement with a worm 15. The worm is mounted upon a shaft 16, which may be rotated in either direction at will. The driving means for the shaft 16 may, if

desired, include a shaft 17, having bevel gear connections with the shaft 16 and also having bevel gear connections with a shaft 18 disposed adjacent the outer vertical wall of the platform. At the upper end of the shaft 18, there is mounted a handle 19 having bevel gear connections with the shaft 18 for driving the latter.

Within the groove 12, I provide two concentric annular clamping members 20 and 21, each adjustable to vary its diameter in respect to the other clamping member and adjustable to vary its diameter in respect to the inner platform section 11. The inner clamping member 20 is adapted to be disposed within the lower edge of the skirt, while the outer clamping member 21 is adapted to be disposed outside of the skirt. Each clamping member is formed of a series of slotted plates 22, connected together by pins or bolts extending through the slots, so that the diameters of the clamping members may be varied at will by sliding the plates past each other. For supporting and adjusting the position of the inner clamping member 20, each alternate plate 22 thereof is connected to a radially-movable slide 23, supported by the platform and movable in a corresponding groove or slot 24 in the platform, so that the elevation of the slides and the clamping member cannot be varied, but by moving inwardly or outwardly the several slides, the diameter of the inner clamping member may be varied at will, and, further, may be caused to assume any irregular shape due to the flexibility of the plates 22. Each alternate plate is connected to its corresponding slide by a substantially U-shaped bar 25, whereby the slide does not interfere with the draping of the skirt over the inner clamping member. Each alternate plate of the outer clamping member is connected to a corresponding slide 26, and each slide 26 is carried by and movable longitudinally in respect to the corresponding slide 23. Each slide 23 is provided with oppositely-disposed upwardly and inwardly-extending side flanges which engage with the side edges of the slide 26 and with a portion of the upper surface thereof whereby the slide 26 is normally held in engagement with the slide 23, so as to be moved with the latter but whereby said slide 26 may be moved independently of the slide 23 when desired. By moving the slides 23, the adjustment of the two clamp-

ing members in respect to each other is not varied, as the slides 26 are carried by the slides 23, but when the inner clamping member has been adjusted to the desired position and shape, the slides 26 may be moved inwardly to bring the outer clamping member toward the inner clamping member to firmly grip the lower portion of the skirt between the two clamping members, to hold the same while it is being marked. The inner clamping member is of slightly greater height than the outer clamping member, so that when the skirt is gripped between the two, as illustrated in Fig. 2, pieces of chalk or other marking means may be pressed against the skirt at the upper edge of the outer clamping member, and the skirt will be supported from the inside by the upper portion of the inner clamping member. Thus, the outer member constitutes a guide for the chalk, while the inner member constitutes a support for the cloth while it is being marked.

By making the central platform 13 and the markers relatively movable in a vertical direction, and preferably by vertically adjusting the inner platform, the skirt may be marked, so as to be cut any desired length. If it is desired that the skirt barely touch the ground, the platform 13 is adjusted so that its upper surface comes at substantially the same elevation as the upper edge of the outer clamping member. The skirt may be marked for a greater or less length by raising or lowering the platform. The extent to which the platform is raised or lowered may be indicated in any suitable manner, but, as illustrated, I have provided a pointer 27 carried by the platform 13 and extending out through a vertical slot in the outer wall of the base or platform 10 and adjacent the crank 19, so that as the crank is turned, the variation in elevation may be noted.

Having thus described my invention, I claim as new and desire to secure by Letters Patent:

1. A skirt marker, including a platform and two concentric annular clamping members carried thereby and adapted to grip the lower portion of the skirt therebetween throughout the circumference thereof.

2. A skirt marker, including a platform, two concentric annular gripping members carried thereby and adapted to grip the lower portion of the skirt therebetween, and means for varying the diameters of said clamping members.

3. A skirt marker, including a platform, two concentric annular gripping members carried thereby and adapted to grip the lower portion of the skirt therebetween, and means for varying the diameters of said clamping members without varying their relative adjustment.

4. A skirt marker, including two concentric annular clamping members adapted to

grip the lower portion of the skirt therebetween, and means for adjusting each of said clamping members in respect to the other.

5. A skirt marker, including two concentric annular clamping members adapted to grip the lower portion of the skirt therebetween, the inner of said members extending upwardly to a higher elevation than the outer.

6. A skirt marker, including two concentric annular gripping members adapted to grip the lower portion of the skirt therebetween, and means for simultaneously varying the diameter of both clamping members, and means for varying the diameter of one clamping member in respect to the other.

7. A skirt marker, including two concentric clamping members, one of said members adapted to lie inside of the lower portion of the skirt and the other adapted to lie outside of the skirt and at a lower elevation than the upper edge of said first-mentioned clamping member, and means for varying the diameter of one of said members to grip the skirt therebetween.

8. A skirt marker, including two concentric annular clamping members adapted to grip the lower portion of a skirt therebetween, a platform, and means for varying the relative heights of said platform and said clamping members.

9. A skirt marker, including two annular concentric members adapted to grip the lower portion of a skirt therebetween, a platform, and means for varying the height of said platform in respect to said clamping members.

10. A skirt marker, including two concentric annular clamping members, each formed of a series of plates slidably connected together.

11. A skirt marker, including two concentric annular clamping members, one of said members being formed of a series of plates slidably connected together, and a series of slides connected to certain of said plates and radially movable to adjust the diameter of said clamping members.

12. A skirt marker, including a platform, an inner clamping member formed of a series of plates slidably connected together, slides radially movable in respect to and connected to certain of said plates for adjusting the size and shape of said member, an outer clamping member formed of a series of plates slidably connected together, and slides connected to certain of said last-mentioned plates and carried by the first-mentioned slides for varying the adjustment of one clamping member in respect to the other.

13. A skirt marker having, in combination, a platform an inner clamping member including a curved plate, a slide radially movable in respect to said platform and connected to said plate, an outer clamping mem-

ber including a curved plate, and a slide connected to said plate and carried by the first-mentioned slide for moving said clamping members in respect to each other.

5 14. A skirt marker including a platform, two curved plates constituting clamping members and adapted to grip the lower portion of a skirt therebetween, one of said plates extending to a higher elevation than
10 the other of said plates, and means for vary-

ing the positions of said plates in respect to said platform.

In testimony whereof I have signed my name to this specification in the presence of two subscribing witnesses.
